CLAIM

The ornamental design for a cutting guide, as shown and described.

DESCRIPTION

FIG. 1 is a front, top perspective view of a cutting guide comprising the new design;

FIG. 2 is a back, bottom perspective view of the design of FIG. 1;

FIG. 3 is a front elevational view of the design of FIG. 1;

FIG. 4 is a back elevational view of the design of FIG. 1;

FIG. 5 is a right elevational view of the design of FIG. 1;

FIG. 6 is a left elevational view of the design of FIG. 1;

FIG. 7 is a top view of the design of FIG. 1; and,

FIG. 8 is a bottom view of the design of FIG. 1.

The broken lines immediately adjacent the shaded areas represent the bounds of the claimed design, while other broken lines are directed to the environment subject matter and form no part of the claimed cutting guide design.

1 Claim, 6 Drawing Sheets
